UNITED STATES PATENT OFFICE.

WILLIAM H. COLEMAN, OF BINGHAMTON, NEW YORK, ASSIGNOR TO THE WILKINSON MANUFACTURING COMPANY, OF BINGHAMTON, NEW YORK.

FOLDING OR COLLAPSIBLE SLED.

938,300.

Specification of Letters Patent. Patented Oct. 26, 1909.

Application filed March 24, 1909. Serial No. 485,461.

To all whom it may concern:

Be it known that I, WILLIAM H. COLEMAN, citizen of the United States, residing at Binghamton, New York, have invented 5 certain new and useful Improvements in Folding or Collapsible Sleds, of which the following is a specification.

My invention relates to an improvement in sleds of the type shown in an application 10 filed by me in the United States Patent Office March 3, 1909, Serial Number 481019. In this application I disclosed a collapsible sled, or one in which the runners fold inwardly under the seat so as to be conveniently carried, and one of the important features of novelty and utility consisted in a brace rod extending across between the runners at their front ends, having pivotal connection therewith so as to permit the folding 15 20 25 of the parts without diminishing the effectiveness of the rod in its bracing action. In the present improvement I have utilized the same brace rod, but in connection not only with the collapsible feature but with steering means.

In this connection I do not limit myself to the present improvement as applied to a collapsible sled, as I may utilize the steering feature of the present case with the sled not 30 collapsible if this should be found desirable.

In the drawing, Figure 1 is a bottom view of the sled with one of the runners partially collapsed or folded inwardly. Fig. 2 is a front view, Fig. 3 is a section on line 1—1 35 of Fig. 1.

The frame of the sled is composed of slide bars *a*, runners *b*, and intermediate metal knees *c*. The side bars *a* are securely bolted to the knees *c* and to the turned up forward 40 45 50 end of the runner. The collapsible sections comprising the side bars, runners and knees are pivotally connected through metallic straps *d*, to cross bars *e*. Catches *f*, under the tension of springs *g* serve to keep the collapsible sections in position and to prevent collapsing normally, the catches *f* having notched ends engaging a staple *h* secured to the cross bar. Obviously any other form of catch may be substituted for the 55 one shown. The cross bars *e* serve to support the seat section made in one or more pieces and shown at *i*.

In order to effect the steering of the sled it is necessary to have the runner sections 55 flexible so that they will be allowed a limited

amount of lateral movement to change the direction or course of the sled. In order to secure this effect the seat section is secured to the center and rear cross pieces *e*, but not to the front cross piece, simply resting upon this pieces and this gives greater flexibility to the runners as they extend to a considerable distance beyond the forward cross piece and their first connection is with the center cross piece, so that there is nothing but the 60 65 resistance of the side bars and metal runners to resist the lateral movement.

A clip *k* is secured to each runner near the upper end beneath the side bar, and each clip supports a pivot serving as a connection for 70 the ends of a brace bar *m*. The pivotal connection permits the folding of the runner sections as in my application referred to. The brace bar in the present case I form with an offset *n*, strengthened by a section of 75 metal *o*, and this offset serves to support a steering bar *p*, extending beyond the sides of the sled and having suitable hand grips so as to permit the operator to move the front of the sled from side to side to direct 80 its course. Straps *q* extend between the steering bar and the projecting part of the seat as shown at *r*, the straps being pivotally connected at their rear end to the seat extension and rigidly secured to the steering 85 bar. This connection serves to give a purchase for the steering bar in the throwing of the sled runners from side to side.

I do not limit myself to a sled having its runners collapsible as the steering mechanism may be applied to a non-collapsible sled with equally good effect though it will not be as complete an article. 90

It will be observed that the brace bar *m* is secured to the runners below the top of the 95 sled and this gives me a greater purchase upon the runner sections through the medium of the steering bar.

What I claim is:

In a sled, collapsible runner sections, cross 100 bars supporting the same, a seat, a connection extending between the front of the runners and a steering bar supported thereby, substantially as described.

In testimony whereof, I affix my signature 105 in presence of two witnesses,

WILLIAM H. COLEMAN.

Witnesses:

GEO. L. NELSON,

THOMAS J. MANGAN.
